UNITED STATES PATENT OFFICE.

CHARLES WILLIAM GODSON LITTLE, OF ENFIELD, ENGLAND.

CARBURETOR.

Application filed December 27, 1919. Serial No. 347,813.

To all whom it may concern:

Be it known that I, CHARLES WILLIAM GODSON LITTLE, a subject of the King of Great Britain and Ireland, and resident of 5 Enfield, England, have invented new and useful Improvements in Carburetors, of which the following is a specification.

This invention relates to certain improvements in carburetors, and the nature and 10 objects of the invention will be readily understood by those skilled in the art in the light of the following detailed description and explanation of the accompanying drawings illustrating what I at present believe 15 to be the preferred embodiments or mechanical expressions of my invention from among other forms, arrangements, combinations, and constructions within the spirit and scope thereof.

20 The present invention relates particularly to carburetors for internal combustion motors and includes as one of its objects the provision of such a carburetor in which the proportions of air and fuel forming the 25 combustible mixture supplied to the motor are varied by the operation of the throttle member which controls the supply of combustible mixture from the carburetor to the motor so that a proper combustible mixture 30 is formed for each position of the throttle throughout the working range of the motor.

A further object of the invention is to 35 provide a carburetor in which means for admitting air to the fuel before discharge into the mixing chamber of the carburetor to form a primary mixture, is controlled by the throttle to vary the proportions of air and fuel forming the primary mixture discharged into the mixing chamber in relation 40 to the position of the throttle, and which means is adjustable independently of the throttle to permit variation of the proportions of fuel and air forming the said primary mixture throughout the working range 45 of the throttle.

A further object of the invention is to 50 provide a carburetor in which the proportions of air and fuel forming the combustible mixture are varied by the operation of the throttle, with auxiliary and independently operable means for varying the combustible mixture proportions for heavy load 55 operating conditions without disturbing or affecting the normal adjustment of the carburetor for light load operating conditions.

A further object of the invention is to

provide a carburetor with independent adjustable air admission means for admitting air directly to the carburetor mixing chamber to vary the combustible mixture when 60 the main air admission port of the carburetor is restricted by the position of the throttle to operate a motor for light load conditions.

A still further object of the invention is 65 to provide certain improvements in the construction of the fuel and air intake passages of a carburetor and in the construction and mounting of the discharge nozzle or orifice whereby a proper and complete atomization 70 of the liquid fuel is obtained.

A still further object of the invention is to provide certain improvements in the construction and mounting of the carburetor body and the float chamber and in the manner of operatively connecting and arranging 75 these elements thereof.

Various other objects and advantages will appear and be readily recognized and appreciated by those familiar with this art 80 from the following detailed description and explanation of the accompanying drawings.

Fig. 1 is a vertical section, certain parts being shown in elevation.

Fig. 2 is a top plan, the float chamber of 85 the carburetor being omitted.

Fig. 3 is a side elevation.

Figs. 4 and 5 are sectional views of certain details of construction.

Fig. 6 is a detail sectional view taken on 90 the line $x-x$ of Fig. 1.

The carburetor comprises the body 1 provided with the main air inlet 2 at the lower part thereof extending through one side of the body 1 and in open communication with 95 the atmosphere. The main air inlet 2 at its upper end is in direct communication with and discharges into the mixing chamber of the carburetor, so that an air supply passage is formed from atmosphere through one 100 side of the body 1 and passing into and upwardly through the body, to and discharging into the carburetor mixing chamber.

The body 1 is formed with a lateral extension 6 extending horizontally from the lower portion of the body and the member 7 extending vertically from the outer end portion of the member 6. The member 7 is joined at its upper end portion with the 105 main portion of the body 1 and is hollow throughout its length to form a vertically

disposed fuel well. The member 6 is likewise formed to provide a horizontally disposed fuel passage at its outer end in communication with the lower end of the vertical well formed by the member 7. The fuel passage formed by the member 6 extends inwardly a distance into the lower end of the body 1 and below the main air passage and inlet 2.

- 10 A float chamber 3 is connected with and arranged to supply fuel to the passage formed in the member 6. The float chamber 3 is provided with the hollow lateral extension 4 which is secured by means of set screws or similar fastening means to the end of the carburetor body 1 below the fuel passage formed by the member 6. The lateral extension 4 is connected and in communication with the fuel passage formed by the member 6, by means of a passage or duct formed in the extension 4 and communicating with the fuel passage in the member 6, so as to discharge fuel from the float chamber 3 into the passage in the member 6.
- 15 It will be noted here that the hollow extension 4 not only forms a conduit for passage of fuel from the float chamber to the fuel passage in the body 1 and member 6, but also provides the means by which the float chamber 3 is attached to and supported from the carburetor body 1.

The outer end of the passage formed in the member 6 adjacent its point of discharge into the lower end of the vertical well 7 is closed by a screw plug 5 provided with a small longitudinal duct 5^a forming a continuation of the passage in the member 6 and providing a restricted passage communicating with and discharging into the lower end of the well 7 from the fuel passage in the member 6. Access to the plug 5 for removal, replacement, or the like, is provided for by a screw threaded opening in the wall of the member 7 opposite the plug 5 and normally closed by a removable screw threaded plug or cap 8.

In the particular type and arrangement illustrated in the accompanying drawings, a throttle member 9, which comprises a cylindrical portion or plug having a diametrical bore extending therethrough, is rotatably mounted in the body 1, above and extending across the main air inlet 2, to control the size of the passage therethrough.

55 A lever 10 is mounted on and fixed to the throttle member 9 by means of which the same is operated to control the passage of air passing through the bore of the member 9 from the air inlet and passage 2, in the body 1.

The upper end of the vertical fuel well 7 is closed and a conduit or pipe 11 is mounted therein and is provided with a portion 11^a extending therethrough a distance into the well 7. The pipe 11 extends longitudinally and axially a distance through the member 9, which is freely rotatable around the pipe 11, and terminates within the diametrical bore forked through the plug portion of the member 9 and adjacent the proximate wall of the bore. In this manner, the pipe 11 provides a connection between the vertical fuel well 7 and the mixing chamber, through which air and fuel pass from the well 7 to the mixing chamber where it is discharged and mixes with air passing through the chamber from the main air inlet and passage 2. The throttle 9 is rotatably mounted in the body 1 by means of spindles or shafts in suitable bearings or journal boxes formed in the body 1. The spindle or shaft which supports the end of the member 9 through which the pipe 11 passes is formed by a hollow extension or sleeve 12 mounted in a bearing formed in the body 1 and the pipe 11 extends longitudinally through the sleeve 12 into the plug portions of the member 9, as hereinbefore described.

A passage or duct 13 is formed in the body 1 and extends from a point in the bearing in which the sleeve 12 is mounted to the upper end of the vertical fuel well 7. The sleeve 12 is provided with a preferably V- or triangular shaped opening 14 therethrough and so positioned therein as to be opposite the open end of the duct 13 in the bearing of the sleeve 12 formed in the body 1. The foregoing arrangement of the opening 14 in the sleeve 12 and the end of duct 13 being such, that in certain positions of the throttle 9, the opening 14 will register with the open end of the duct 13 to permit air to pass therethrough and into the fuel well 7. The position of opening 14 with respect to the end of duct 13, determines the amount of air permitted to pass therethrough into the well 7 and varies from complete registration of opening 14 with the end of duct 13, through the various positions through which the opening 14 moves to a position of non-registry with the duct 13 with the sleeve 12 substantially closing the duct against entrance and passage of air therethrough into the fuel well 7. The position of the opening 14 in the sleeve 12 is such that, when the throttle is in open position with the bore thereof in full alignment and registry with the main air inlet 2, the opening 14 is not in registry with the end of duct 13 and the sleeve 12 substantially closes the duct against passage of air to fuel well 7 and when the member 9 is in closed position, that is the smallest working opening between inlet 2 and the mixing chamber, the opening 14 is in complete registry with duct 13 and air is supplied to well 7 at the maximum capacity of the duct 13. The amount of air supplied to well 7 varies proportionally, between the two ex-

treme positions above referred to, with the position of the throttle 9. Preferably, the end of the duct 13 which registers with the V-shaped or triangular opening 14 in the sleeve 12, is of a similar V or triangular shape, so that when the throttle 9 is in open position the point or apex only of the triangular openings may be in registry to permit a very small, comparatively negligible amount of air to enter the duct 13 and fuel well 7. However, the invention is not limited to the particular shape of the opening 14 and the adjacent end of duct 13, as any suitable or desired shape may be utilized.

15 A flanged sleeve 15 is mounted and confined within the hollow shaft extension or sleeve 12 of the throttle 9 and is angularly adjustable with respect thereto. A screw 16 extends through an elongated transverse slot cut in the sleeve 12 and confines the sleeve 15 in position within the sleeve 12. The screw 16 permits of angular adjustment of the sleeve 15 and provides means for locking the same in the desired adjusted position. The sleeve 15 is provided with an opening 17 through its wall and the sleeve is so positioned within the sleeve 12 that the opening 17 registers with the opening 14. The area of the opening 14 is variable by adjusting the position of the sleeve 15 and opening 17 with respect thereto so as to completely register therewith or partially cover the same to decrease the size of the opening and the amount of air which passes therethrough. From the foregoing, it is apparent that the sleeve 12 is so arranged that with the throttle 9 in closed "light load" position the opening 14 therein is in full registry with the air duct 13 and that when the throttle 9 is in open "heavy load" position, the opening 14 is practically out of registry with the duct 13 to cause formation and supply of a combustible mixture of maximum richness due to the need for such mixture at high speed of a motor, or heavy load as well understood by those skilled in this art. Now, by the use of the adjustable sleeve 15 the size or area of the opening 14 can be varied to permit adjustment of the carburetor to meet the requirements of a particular motor or for peculiar working conditions.

55 A hollow extension 18 on the body 1 is in communication at its inner end with the duct 13 and is provided with an opening in its outer end portion which communicates with the atmosphere and provides an air inlet opening for the admission of air to the hollow extension 18.

60 A needle valve 19 is adjustably mounted in the extension 18 and controls the admission of air through the inlet in the extension 18 to the duct 13. The valve 19 is adjusted when setting the carburetor and provides a normally fixed air admission means but which may be varied on occasions, independent of the adjustments of the sleeves 12 and 15, to the duct 13 and fuel well 7. The valve 19 and extension 18 provide for the variation of the fuel mixture for heavy load working conditions without materially affecting whatever adjustments are made for light load conditions by means of the adjustable sleeve 15 and opening 17. The sleeve 15 with the throttle in open position for "heavy load" operation of the motor is in a position substantially closing the duct 13 against admission of air to vary the mixture in the fuel well 7, therefore, in order to make any desired adjustment for "heavy load" conditions the valve 19 is operated to admit air to the well 7, and it is clear that this adjustment will have but small effect upon the adjustment made by the sleeve 15 for "light load" conditions with the duct 13 open to admit the entry of comparatively large quantities of air to the well 7.

65 An air passage 20 is formed in the body 1 and is provided with an air inlet 21 open to atmosphere through a side of the body. A slidable plate 23 having an opening adapted to be moved to and from registration with the inlet 21 to vary the amount of air admitted thereto or to completely shut off the same, is adjustably mounted on the body 1 over the opening or inlet 21. The throttle 9 is provided with a duct 22 which connects the air passage 20 with the mixing chamber, so that, with the inlet 21 open air passes from atmosphere to the passage 20 and through duct 22 into the mixing chamber where it is mixed with the air and fuel passing therethrough.

70 The air passage 20 provides an additional means for admitting air into the mixing chamber other than by the main air inlet 2. When the throttle is in open "heavy" load position, opening of the passage 20 will have practically no effect on the mixture formed as the quantity of air admitted thereby is comparatively small compared to the quantity admitted through inlet 2, but when the throttle 9 is in partially closed "light" load position the quantity of air admitted to the mixing chamber is materially reduced so that opening of passage 20 will have considerable effect in varying the mixture formed. Hence, air passage 20 provides an additional adjustment increasing the range through which the mixture at "light" load positions of the throttle can be varied.

75 A hollow projecting member 24 is arranged on the body 1 in communication with the fuel well 7. Any suitable vacuum gauge may be mounted in and connected with the hollow member 24 to indicate the degree of vacuum existing in the fuel well 7, and hence by suitable calibration, as will

be readily understood by those skilled in the art, the vacuum in the well can be readily determined. It will be understood, of course, that the hollow member 24 is normally closed, either by a vacuum gauge or in any of a number of well known ways.

The operation of a carburetor embodying the various features of my invention as hereinbefore referred to and described will now be explained. The arrangement and mounting of the screw plug 5 provided with the duct 5^a therethrough forms a constriction in the passage formed by the member 6 and offers resistance to the flow of fuel therethrough from the float chamber 3 to the fuel well 7. With a motor to which the carburetor is connected at rest, fuel flows from the float chamber 3 to the vertical fuel well 7 to a level therein corresponding to the level in the float chamber, as will be readily understood, which level is above the lower end of the pipe 11. When a motor is started, therefore, solid fuel is drawn by suction created by the motor from the fuel well 7 and discharged into the motor until the level of fuel in the well is lowered below the end of the pipe 11, after which air is drawn into the well and mixed with the fuel sucked therefrom as will be explained hereinafter. During the operation of the motor fuel continues to flow from the float chamber 3 through the passage formed by the member 6 and the duct 5^a forming a constriction therein and into the fuel well 7. Fuel is drawn by suction created by the motor from the fuel well 7 through the pipe 11 mixing with the air therein the emulsion thus formed being discharged into the diametrical bore of the throttle member 9 where it is mixed with air passing therethrough from the main air inlet 2 to form a combustible mixture which is drawn into the motor and there ignited, in a manner well known and understood by those skilled in this art.

Assume that a motor with which the carburetor is operatively connected is working lightly loaded, and at low speed, then the throttle 9 is in partially closed position with a maximum choke effect, that is, the passage through the throttle 9 is materially reduced in area which reduces the quantity of air drawn into the passage in the throttle 9 from the main air inlet 2. Now, with the throttle in the above position the opening 14 in the sleeve 12 is in registry with the duct 13 to permit approximately maximum flow of air to the duct 13 and well 7, as hereinbefore described, and explained. Thus, it is seen that with the throttle 9 in "light" load position and the resulting reduced quantity of air passing into the throttle passage, that the quantity of fuel drawn from the well 7 for mixing therewith in the throttle passage is propor-

tionately reduced to form the proper combustible mixture for operating the motor, by the quantity of air admitted to the fuel well through opening 14 and duct 13. As the throttle 9 is opened to increase the speed and power of the motor and increase the quantity of air drawn from the main air inlet 2, the sleeve 12 is rotated and correspondingly reduces the area of the opening 14 in registry with the duct 13, so that the quantity of air admitted to the well 7 from atmosphere is reduced and the quantity of fuel drawn from the well 7 through pipe 11 and discharged into the passage through throttle 9 is correspondingly increased to form a proper combustible mixture with the air from the main air inlet 2. When the carburetor of the invention is operating with a motor working at maximum speed or heavy load the throttle 9 is in open position with the passage therethrough in registry with the main air inlet 2, so that a maximum quantity of air passes therethrough. In this position of the throttle the sleeve 12 is rotated to position with the port or opening 14 substantially out of registry with the duct 13, so that the well 7 is practically cut off from communication with the atmosphere and substantially no air is drawn into well 7. This results in maximum quantity of fuel being drawn into the passage through throttle 9 for mixing with the increased quantity of air admitted from air inlet 2 to form a proper and efficient combustible mixture for operating the motor at maximum speed or "heavy" load. It will be apparent from the foregoing that the operation of the carburetor between the two extremes of maximum "light" load and maximum "heavy" load provides for varying the proportions of fuel and air forming the combustible mixture corresponding to the requirements of the motor at the speed or load at which it is operated.

The rotatable sleeve 15 provided with the port or opening 17 forms the means for adjusting the carburetor for "light" load or low speed operating conditions. By rotating the sleeve 15 the area of the port or opening 14 in the sleeve 12 can be varied to regulate the quantity of air admitted to the well 7 through duct 13 from atmosphere and when the proper adjustment has been made the sleeve 15 is set at that point by means of the set screw 16.

The combustible mixture at heavy loads may be regulated by means of the needle valve 19 to increase or reduce the air admitted into the fuel well 7 through member 18 and duct 13. It is clearly seen that any adjustment of needle valve 19 will have no material effect on or disturb the adjustment of the carburetor for "light" load operations, as at "light" loads the duct

13 is in partial or substantially complete registration with the opening 14 in sleeve 12 and therefore, the relatively small added admission of air by needle valve 19 will 45
inlet and operated by the said throttle, and means for adjusting the area of said fuel well inlet independently of the operation of said valve by the said throttle.

5 2. In a carburetor, a mixing chamber, a throttle controlling the discharge of combustible mixture from said mixing chamber, a fuel well, a fuel supply pipe from said well to and discharging into said mixing chamber, and means for admitting air to said fuel well to form a primary mixture 50
therein for discharge into said mixing chamber, the said air admission means consisting of a passage open to atmosphere and communicating with said fuel well, a valve operated by said throttle for decreasing the area of said fuel well air passage as the throttle is opened and for increasing the area thereof as the throttle is closed, adjusting means for varying the maximum area of said passage independently of said 55
throttle operated valve, and auxiliary means for admitting air to said fuel well independently of said throttle operated air admission means.

10 3. In a carburetor, a mixing chamber, a throttle controlling the discharge of combustible mixture from said mixing chamber, a fuel well, a fuel supply pipe from said well to and discharging into said mixing chamber, and means for admitting air to said fuel well to form a primary mixture 60
therein for discharge into said mixing chamber, the said air admission means consisting of a passage open to atmosphere and communicating with said fuel well, a valve operated by said throttle for decreasing the area of said fuel well air passage as the throttle is opened and for increasing the area thereof as the throttle is closed, adjusting means for varying the maximum area of said passage independently of said 65
throttle operated valve, and auxiliary means for admitting air to said fuel well independently of said throttle operated air admission means.

15 4. It is evident that various changes, modifications and variations might be resorted to without departing from the spirit and scope of my invention and hence I do not wish to limit myself to the exact disclosures hereof.

20 5. Desiring to protect my invention in the broadest manner legally possible what I claim is:

25 1. In a carburetor, a mixing chamber, a throttle controlling the discharge of combustible mixture from said mixing chamber, a fuel well, a fuel supply pipe from said well to and discharging into said mixing chamber, means for admitting air to said fuel well to form a primary mixture 70
therein for discharge through said fuel supply pipe into said mixing chamber, the said air admitting means consisting of an inlet from atmosphere for discharging air into said fuel well, a valve controlling said 75
